UNITED STATES PATENT OFFICE.

WALTER H. BOWMAN, OF PHILADELPHIA, PENNSYLVANIA.

ARTIFICIAL TOOTH.

1,386,762.

Specification of Letters Patent. Patented Aug. 9, 1921.

Application filed November 1, 1919. Serial No. 335,001.

To all whom it may concern:

Be it known that I, WALTER H. BOWMAN, a citizen of the United States, and a resident of Philadelphia, county of Philadelphia, 5 State of Pennsylvania, have invented certain new and useful Improvements in Artificial Teeth, of which the following is a specification, reference being had to the accompanying drawings.

10 My invention relates particularly to that class of artificial teeth that are adapted to be mounted on a plate or mounting of vulcanite, metal or other suitable material, which may be retained in the mouth of the 15 wearer by any of the well-known means, as, by suction, adhesion or otherwise, and is especially directed to teeth in which the retaining anchor members are formed of metal and attached to the tooth body after the 20 biscuit tooth has been baked or fired, and reduced to a porcelain state.

The principal objects of my invention are to provide an artificial tooth so formed that its anchor or attaching member may be applied at the time of setting up the denture embodying the teeth, and be separately supplied by the manufacturer, so as to be interchangeably engaged, one with the other, by the operator and be capable of replacement without the necessity of revulcanization.

Other objects of my invention are to provide an artificial tooth whose anchor or attaching member is capable of being formed 35 of an inexpensive metal or alloy, and, therefore, may be relatively larger and consequently stronger than the baked-in platinum pins commonly employed.

My invention further comprehends an artificial tooth having its anchor or attaching member so disposed and extended within the tooth body as to distribute the strains on the porcelain, which are incident to biting or chewing, and which tend to fracture teeth 45 at the region of engagement with their attaching members.

My invention includes an artificial tooth having an attaching member arranged to yieldingly expand within the tooth body 50 and be thereby frictionally engaged therewith and held firmly against the walls thereof.

My invention further includes an artificial tooth having an anchor or attaching mem-

ber arranged to be inserted within a suitably formed recess in the tooth body and be automatically locked and retained therein, and thereby prevented from accidental displacement.

The form of my invention as hereinafter described, comprehends an artificial tooth having a recess extending longitudinally therein toward its incisive edge, and having its lateral and incisive walls undercut to receive an anchor or attaching member which is preferably of I-beam cross section, having a central web terminating along its opposite edges in oppositely extended flanges, the flanges along one side of said web being arranged to extend behind the undercut walls of the recess in the tooth body and being extended longitudinally beyond the web so as to project incisively behind the pin guard of the tooth body, said extension being provided with a spring tongue bent backwardly and arranged to frictionally engage the labial wall of said recess, to thereby hold the flange frictionally engaged against the lingual wall of said recess, and said tongue being arranged to engage a notch or shoulder in said recess to prevent the accidental displacement of the attaching member from the body of the tooth.

My invention also includes all of the various novel features of construction and arrangement as hereinafter more definitely specified.

In the accompanying drawings, Figure 1 is a central longitudinal sectional view of a tooth adapted to receive an attaching anchor member constructed in accordance with my invention; Fig. 2 is a view similar to Fig. 1 showing the attaching anchor member applied thereto; Fig. 3 is a transverse sectional view of said tooth and attaching anchor member taken on the line 3-3 in Fig. 2; Fig. 4 is a perspective view of said attaching anchor member; and Fig. 5 is a longitudinal sectional view showing the tooth engaged with a vulcanite plate by the attaching anchor member which, for convenience of illustration, is shown in elevation.

In said figures, the tooth body 1 comprises the "bite" 2, which is curved to simulate a natural human tooth, a "ridge-lap" 3, and a plane lingual surface forming the "shut" 4 intersecting the "ridge-lap" 3 at its linguo-gingival termination, and terminat-

ing linguo-incisively in the "pin guard" 5, which forms the linguo-gingival termination of the "bite" 2.

The tooth body 1 is provided with an undercut retaining recess 6 which extends into the tooth body through the gingival surface or "ridge-lap" 3, and which is connected with a relatively narrow slot 7, opening through the lingual wall or "shut" 4, and 10 as clearly shown in the drawings, extends incisively behind the "pin guard" 5 to form the pocket 9.

The tooth body formed as shown, is adapted to be provided with an attaching member, which may be engaged therewith after the tooth has been baked or fired, and reduced to the porcelain state. Said anchor member, as best shown in Fig. 4, is preferably in the form of an I-beam, and may be 20 conveniently cut from lengths of wire of I-beam cross section, and comprises the web 10, terminating lingually in the laterally extended flange 11 and labially in a similar flange 12, which not only extends laterally 25 in opposite directions from the web 10, but also projects incisively into the pocket 9, and returned upon itself to form the spring tongue 13, which may be preferably curved away from the flange 12 at its free end 15, 30 to engage a suitably formed notch or shoulder 16 in the labial wall of the recess 6, as shown in Fig. 5.

As best shown in Fig. 5, the mounting 17 of vulcanite or other suitable material may 35 be packed into the recess 6 between the flange 12 and tongue 13, and around the flange 11, so that, as will be obvious, when the denture is vulcanized, the tooth body 1 will be securely engaged with the denture plate by 40 the attaching anchor member.

It may be here noted that the spring tongue 13 tends to maintain the surface of the flange 12 in contact with the undercut surfaces of the recess 6, and not only frictionally retains said anchor member with 45 the tooth, but prevents the material of which the denture plate 17 is formed from entering between the flange and the tooth surface.

It will be obvious that a tooth thus formed 50 may be provided with anchor members formed of different metals, and the tooth stock may be maintained in various shades and separately sold as required, being applied by the operator at the time when the 55 tooth is set up for vulcanization.

Furthermore, my invention is advantageous in that should the porcelain tooth become broken, it may be readily replaced by slipping another tooth into its place with

cement in the recess 6 to form a cemented 60 connection with the attachment remaining embedded in the denture plate 17, so that it is unnecessary in case of a broken tooth to revulcanize the denture plate whereby a replacement of the tooth may be accomplished within a few minutes which otherwise would require several hours time should revulcanization be necessary.

I do not desire to limit my invention to the precise details of construction and arrangement as herein set forth, as it is obvious that various modifications may be made therein without departing from the essential features of my invention as defined in the appended claims.

Having thus described my invention, I claim:—

1. An artificial tooth comprising an attaching anchor member having a shank arranged to extend lingually from said tooth, 80 and provided with a flange extending laterally and incisively from said shank, and arranged to engage undercut surfaces of a recess in the body of said tooth, said flange being bent to form a yielding tang arranged 85 to frictionally engage said member with the surfaces of said recess.

2. An artificial tooth comprising an attaching anchor member engageable with a suitably formed recess therein after it has 90 been reduced to the porcelain state, said anchor member having a flanged web arranged to project lingually from said tooth, and having a yielding projection arranged 95 to extend incisively into the body of said tooth, and to frictionally engage said anchor member with the walls of said recess.

3. A tooth-attaching anchor member in the form of an I-beam, having one of its flanges extended longitudinally beyond its 100 web portion, and returned upon itself to form a spring tongue.

4. In combination with a base plate, an artificial tooth, said tooth being provided with a T-slot extending longitudinally thereof along its shut surface, an attaching anchor extending from said T-slot lingually into the body of the base plate, said anchor being provided at its labial end with an incisively projecting resilient element bent 110 backwardly upon itself.

In witness whereof, I have hereunto set my hand and seal this 27th day of October, A. D. 1919.

WALTER H. BOWMAN. [L.S.]
